Attn:

UNITED STATES PATENT OFFICE

LEWIS H. SCURLOCK, OF CHICAGO, ILLINOIS

DESIGN FOR A GROUP CONTAINER

Application filed March 21, 1932. Serial No. 43,253. Term of patent 14 years.

To all whom it may concern:

Be it known that I, LEWIS H. SCURLOCK, a citizen of the United States, and resident of Chicago, in the county of Cook and State of Illinois, have invented a new, original, and ornamental Design for a Group Container, of which the following is a specification, reference being had to the accompanying drawing, forming a part thereof:

Fig. 1 is a top or plan view of a group container showing my new and ornamental design.

Fig. 2 is a rear elevation of said group container.

Fig. 3 is a side elevation of said group container.

The ornamental design consists of a hexagonal group container having two flat and

inwardly converging radial sides of equal area, disposed not over eighty degrees apart, a rounded outer side, all relatively wide, and three relatively narrow and rounded intermediate sides curved on the line of a circle struck from the vertical axis of the container, with rounded corners between all of said sides, and with the inner edge of the rim or mouth of the container following said external contour of the container, when viewed from above, said outer curved side coinciding with a circle struck from the center or vertical axis of the group, to which axis the two flat sides converge.

I claim:

The ornamental design for a group container, as shown and described.

LEWIS H. SCURLOCK.
